ILLUMINATING FIXTURE

Harold W. Rambusch, Lloyd Harbor, and Joaquin Santos, Garden City, N.Y., assignors to Rambusch Decorating Company, New York, N.Y., a corporation of New York

Application June 30, 1958, Serial No. 51,593

Term of patent 14 years

(Cl. D48—4)

Fig. 1 is a perspective view of the illuminating fixture showing our new design;

Fig. 2 is an enlarged side elevational view thereof; and

Fig. 3 is a bottom plan view thereof as shown in Fig. 2. What is claimed is:

The ornamental design for an illuminating fixture, as shown.
